J. SYLVAN

VENTILATOR FOR SAW TOOTH SKYLIGHTS

Filed June 13, 1923

Freritor
Joseph Sylvan
by Clara E. Melville, Atty.

UNITED STATES PATENT OFFICE.

JOSEPH SYLVAN, OF CICERO, ILLINOIS.

VENTILATOR FOR SAW-TOOTH SKYLIGHTS.

Application filed June 13, 1923. Serial No. 645,161.

To all whom it may concern:

Be it known that I, JOSEPH SYLVAN, a citizen of the United States, and a resident of Cicero, county of Cook, and State of Illinois, have invented certain new and useful Improvements in Ventilators for Saw-Tooth Skylights; and I do hereby declare that the following is a full, clear, and exact description thereof, reference being had to the accompanying drawings, and to the letters of reference marked thereon, which form a part of this specification.

This invention relates to improvements in ventilators for saw tooth skylights and consists of the matters hereinafter described and more particularly pointed out in the appended claims.

One of the objects of the present invention is to provide an efficient ventilator construction for saw tooth skylight which may be readily built into new skylights or may be readily applied to such skylights as are now in use without the necessity of making material changes therein.

A further object of the invention is to so construct the ventilator that it will in no manner interfere with the passage of light through the panels of the skylight.

Still another object of the invention is to so arrange the parts of the ventilator with reference to the skylight, that either an intake of outside air or an exhaust of inside air may be had as desired.

These objects of the invention, as well as the many advantages thereof will more fully appear as I proceed with my specification.

In the drawings:—

Figure 1 is a transverse vertical section through a saw tooth skylight to which my improved ventilator construction has been applied.

Figure 2 is an enlarged view of the top end of Figure 1 with some of the parts thereof in a changed position.

Referring now in detail to that embodiment of the invention illustrated in the accompanying drawings:—5 indicates a building roof and 5^a indicates as a whole, a "saw tooth" skylight thereon. Said skylight includes a face or wall 6 usually arranged at an angle of 30° relative to the plane of the building roof 5^a, and an angularly disposed roof portion 7 arranged at a right angle to the plane of the face or wall 6. Said skylight may be made of any suitable material

and is illustrated herein as made of concrete. The face 6 has an opening 8 therein which is divided off into suitable lengths or spaces by horizontally spaced bars 9, said bars also acting to reinforce the saw tooth skylight 60 as a whole. 10 indicates the prepared roofing covering the building roof and the roof section 7 of the skylight. Ordinarily, transparent panels 11 are associated with said opening 8 for the purpose of admitting 65 natural light into the space or room below the skylight and said panels are usually hinged along their top edge to the head 6^a of the face wall 6 so that the bottom edge thereof may be swung outwardly. The construction above described sets forth in general, the well known saw tooth skylight construction.

Such skylights are generally recognized as the most efficient means for the entrance 75 of natural light into the work shop or room beneath the same, and this is the primary consideration in their use, the ventilation afforded thereby being secondary in consideration and being of a minimum in efficiency 80 when compared with other means mounted on the roof for ventilating purposes.

In applying my improved ventilator to such skylights, after removing the light admitting panel 11, I secure to the outer surface of the head 6^a of the face wall 6, a plurality of longitudinally spaced substantially rectangular open frames 12. Each frame includes downwardly and outwardly inclined rafter bars 13, 13, with one rafter 85 connected to a short leg 14 which is secured to the head 6^a, and with the other rafter connected to a longer leg 15, the said legs being connected together in the plane of the top part of the opening 8. The frame is 90 braced in the vertical median plane of the rafters by an upright post 16 which is secured at its bottom end to the leg 15 and near its top to the peak of the rafters, the top end 16^a projecting a suitable distance 95 above said peak.

Secured to the longer leg 15 of all of said frames near their connection with the associated rafter bars 13 is a longitudinally extending apron or plate 17, the outer margin of which is formed to provide a flange 18 which projects beyond the plane of the associated rafters. The other margin of said apron terminates about midway between the ends of the legs 15 and is there formed 110

to provide a downwardly opening, flanged channel or groove 19 which is spaced outwardly from the head 6^a of the face wall 6.

Secured to the face wall 6 near the bottom part of the opening 8 is a combination channel and flashing strip 20, said strip overlapping the roofing material 10 on the building roof to make a water tight joint at the junction of the building roof and face wall.

- 10 The panel 11 is inserted in position with its top margin engaged in the channel 19 of the apron and its bottom margin is inserted in position into the upwardly opening channel of the combination strip 20. The panel is 15 rigidly held in this position, which more closely approaches the vertical than does the face wall 6^a so that the top margin of the panel is spaced from the head 6^a to provide an upwardly opening ventilation passageway 21 which communicates with the opening 8.

22 indicates a flashing strip which is secured to the top surface of the roof portion 7 of skylight near the head 6^a, said strip 25 overlapping the roofing material 10 on said roof portion. Said flashing strip includes an outstanding flange 23 which is oppositely disposed with respect to the flange 18 of the apron 17.

- 30 24, 24 indicate ventilator sections each of which include inner and outer angle bars 25, 26 respectively. Said bars are connected by longitudinally spaced glazing bars 27 and mounted on said bars in any suitable manner. 35 are the panels 28 preferably of glass. Secured to the inner angle bars 25 are ears 29 which are pivoted to the top ends 16^a of the upright posts 16 by means of pins 29^a. The space between said ventilator sections is 40 closed or bridged by a flexible ridge strip 30 which accommodates itself to the relative movements between said sections. When the panel sections are in their normally closed position, the outer angle bars 26 rest and engage upon the flanges 18 and 23 of the apron 17 and flashing strip 22 respectively, as illustrated in Fig. 1.

50 Any suitable means may be employed for swinging said sections into their open or closed position, either individually or collectively, but preferably I employ the means illustrated in my prior Patent No. 1,410,625 issued on March 28, 1922. As said means is fully illustrated and described in said patent, I have only shown and will only describe the same in general, here.

- 55 31, 32 indicate arcuate rock bars, concentric with the axis pins 29^a and which are connected at their outer ends to associated glazing bars 27, 27 of the ventilator sections 24. 33 indicates a spur pinion fixed to a longitudinal shaft 34 which is journaled on the upright posts 16. Said shaft has secured to it a pulley wheel 35 which may be rotated in either direction by means of an

endless actuating chain 36 which hangs down through the passageway 21 and opening 8 to extend into the space beneath the skylight within convenient reach of the person desiring to operate the same. The rack 70 bars 31 and 32 are held in engagement with the pinion 33 by means of a bracket 37 (see Fig. 2) and said rack bars also have parts by means of which either one of said sections may be opened individually or both 75 sections may be opened at the same time, as described in said patent before mentioned.

In Figure 1, both sections are in their closed position. Should it be desired to take in fresh air from the outside atmosphere, one of the sections 24 may be opened as shown in Figure 2, toward the wind so that the wind will blow under said section down through the passageway 21 and through the opening into the space or room 80 beneath the skylight. Should it be desired to exhaust or take air out of said space or room, that section facing away from the wind may be opened so that the wind passes over the top thereof. This will produce a 85 suction action up through the opening 8 and passageway 21 to properly ventilate said space or room.

90 My improved ventilator construction may be readily applied to saw tooth skylights 95 already in use and this without material alteration in the same, it only being necessary to remove the light panel 11 and again set it up in the new position described. Furthermore, it does not interfere with the free 100 entrance of natural light. The entire structure may be made in the shop and easily installed on the job.

105 While in describing my invention I have referred to certain details of mechanical construction and arrangement of parts, I do not wish to be limited thereto except as may be pointed out in the appended claims.

I claim as my invention:

- 110 1. In combination with a saw tooth skylight having a face wall and a roof section, said face wall having an opening therein, a panel section associated with the opening in the face wall and having its top margin spaced from said face wall to provide a 115 ventilation passageway which communicates with said opening, and means normally closing said passageway but capable of being actuated to open said passageway to permit a flow of air through said passageway and opening.

- 120 2. In combination with a saw tooth skylight having a face wall and a roof section, said face wall having an opening therein, a panel section associated with the opening in the face wall and having its top margin spaced from said face wall to provide an 125 upwardly opening, ventilation passageway which communicates with said opening, and means above said passageway which nor-

mally covers the same, said means being capable of being actuated to permit a flow of air through said passageway and opening.

3. In combination with a saw tooth skylight having a face wall and a roof section, said face wall having an opening therein, a panel section associated with the opening in the face wall and having its top margin spaced from said face wall to provide an upwardly opening ventilation passageway which communicates with said opening, and a ventilator construction supported on said skylight above said passageway, said ventilator construction being capable of being actuated to permit either an intake of outside air or an exhaust of inside air through said passageway and opening.

4. In combination with a saw tooth skylight having a face wall and a roof section, said face wall having an opening therein below its head, a panel section associated with said opening and having its top margin spaced from said face wall to provide an upwardly opening ventilation passageway which communicates with said opening, an open frame secured to said head, and a ventilator construction supported on said frame above said passageway, said ventilator construction being capable of being actuated to permit either an intake of outside air or an exhaust of inside air through said passageway and opening.

5. In combination with a saw tooth skylight having a face wall and a roof section, said face wall having an opening therein below its head, a panel section associated with said opening and having its top margin spaced from said face wall to provide

an upwardly opening ventilation passageway which communicates with said opening, an open frame secured to said head, a ventilator construction supported on said frame above said passageway, said ventilator construction including two swinging sections, one arranged on either side of the median plane of said passageway, and means passing down through said passageway and opening for actuating either ventilator section to open and close the same.

6. In combination with a saw tooth skylight having a face wall and a roof section, said face wall having an opening therein below its head, a panel section associated with said opening and having its top margin spaced from said face wall to provide an upwardly opening ventilation passageway which communicates with said opening, an open frame secured to said head, an apron secured to said frame, said apron being constructed to receive one margin of said panel section, and a ventilator construction supported on said frame above said passageway comprising two ventilator sections, one arranged on each side of the median line of said passageway, and means for swinging either ventilator section into an open, or closed position.

In testimony that I claim the foregoing as my invention, I affix my signature in the presence of two witnesses, this 6th day of June, 1923.

JOSEPH SYLVAN.
